UNITED STATES PATENT OFFICE.

HENRY F. HUBBARD, OF SHELTON, CONNECTICUT, ASSIGNOR TO STAR PIN COMPANY,
OF SHELTON, CONNECTICUT, A CORPORATION OF CONNECTICUT.

ROTARY WIRE-STRAIGHTENER.

1,123,297.

Specification of Letters Patent.

Patented Jan. 5, 1915.

Application filed January 26, 1914. Serial No. 814,386.

To all whom it may concern:

Be it known that I, HENRY F. HUBBARD, a citizen of the United States, residing in the city of Shelton, county of Fairfield, and 5 State of Connecticut, have invented certain new and useful Improvements in Rotary Wire-Straighteners, of which the following is a full and clear specification.

My invention relates to rotary wire straighteners adapted to work upon a continuous wire coming from a coil or other supply. Apparatus of this character is commonly employed in conjunction with a mechanism for producing articles such as 15 pins, hooks and eyes, and the like, from wire.

It has already been proposed to straighten a continuous wire by leading it axially into and from a rotating shaft and passing the 20 intermediate portion of the wire between the entrance and exit points over a surface out of alinement with the axis.

My present invention provides certain improvements in wire straighteners of this 25 type.

The improvements contemplated by the present invention include an adjustment for the angle at which the wire is displaced from its axial line on its way through the 30 straightener, and improved construction of the offsetting member over which the wire is led to divert it from the axial line of the rotating shaft.

An apparatus embodying the principles 35 of my invention is illustrated in the accompanying drawing, in which—

Figure 1 is a plan view of a rotary wire straightener; Fig. 2 is a side elevation of through the operating parts; and Fig. 4 is 40 the same; Fig. 3 is a longitudinal section, a transverse section on the line IV—IV, Fig. 3.

Referring more specifically to said drawings, 10 indicates the frame upon which are formed the stepped bearing blocks 11, 12, for the reception of the spindle 13 and the tubular sections 14, 15. The spindle 13 is rotatably held in bearing blocks 11, 12 by cover blocks 16, 17, which are secured by 45 screws 18, 19, and the tubular sections 14, 15 are adjustably fixed against rotation in the bearing blocks 11, 12, by cover blocks 20, 21, which are secured by screws 22, 23. The 50 spindle 13 has tubular ends and within these tubular ends the tubular sections 14, 55

15 are disposed. Bushings 24, are secured within the ends of tubular sections 14, 15, by set screws 25.

It will be apparent that the spindle 13 and bushings 24 are in axial alinement, and that the spindle 13 rotates while the bushings are stationary. The wire to be straightened is led from suitable guides into the apparatus through the bushings in tubular member 15 and it is withdrawn from the apparatus through the bushings in tubular member 14. Between the tubular members 14 and 15 the spindle is slotted at 26 and 27 and upon the central portion of the spindle a rotary guide disk 28 is fixed by set screw 70 29. The guide disk 28 is slotted to receive the wire and it is provided with a hub 30 upon which is loosely positioned a free collar 31.

A drive pulley 32 is fixed on spindle 13, 75 in the present instance being shown as mounted over the slotted portion 27 of the spindle and therefore recessed to provide clearance for the wire. The wire in passing from tubular member 15 to tubular member 80 14 is diverted from axial direction by passing through recesses 27, 26 and over the free collar 31, the offset or diverted loop of wire being continuously revolved, about the spindle axis by means of the slotted guide 85 disk 28 without rotating about the axis of the wire. During this revolving operation, the free collar 31 is caused to move relatively to its supporting guide disk 28 by the frictional engagement of the wire with 90 the collar, and due to the non-rotary motion of the wire the collar is caused to have relative rotary motion with respect to the wire. In this way the wear upon free collar 31 is 95 distributed, thus providing against the formation of grooves therein. It will also be apparent that the bushings 24 at the inner ends of the tubular members 14, 15 are subjected to uniform wear by the revolving motion of the loop of wire passing through 100 them. By loosening the screws 22, 23, without the necessity of arresting the operation of the apparatus, the tubular members 14, 15 may be moved toward or away from the free collar 31, thereby adjusting the angle 105 of diversion to which the wire is subjected in passing through the machine.

It will be obvious that the function of the guide disk 28 is to cause the loop of wire to revolve about the axis and that for this pur- 110

pose only one groove is necessary in the disk. In the embodiment shown the disk is provided with two grooves, but any desired number may be provided. Further-
more it will be apparent that the function of the disk is accomplished by engagement of the rear wall of the slot with the wire and that the grooved construction is em-
ployed only as a convenient way of produc-
ing an arm-like projection in the path of
the wire, whereby the loop of wire is caused
to revolve. The tubular members 14 and 15
serve not only as axial guides for the wire,
but also as members for adjusting the angle
through which the loop of wire is led over
the free collar 31, and the mounting of the
members 14 and 15 within the tubular ends
of the spindle 13 provides for the main-
tenance of the bushings 25 in axial aline-
ment during the period of adjustment when
the cover blocks 20, 21 are released to ad-
just the tubular members.

I claim:

1. A rotary wire straightener comprising
in combination a spindle, means for leading
wire to and from said spindle in axial di-
rection, a wire diverting member freely

mounted on said spindle, and means for re-
volving the diverted portion of the wire.

2. A rotary wire straightener comprising 30
in combination a spindle, means for leading
wire to and from said spindle in axial di-
rection, a wire diverting collar freely
mounted upon said spindle, and means for
revolving the diverted portion of the wire. 35

3. A rotary wire straightener comprising
in combination a rotary spindle, means for
guiding the wire to and from said spindle
in axial direction, a free collar disposed on
said spindle for diverting the wire, and 40
means for revolving the diverted portion of
the wire.

4. A rotary wire straightener comprising
in combination a rotary spindle, means for
guiding the wire to and from said spindle in 45
axial direction, a grooved guide disk fixed
to said rotary spindle, and a free collar
loosely mounted on said guide device for
diverting the wire.

HENRY F. HUBBARD.
